UNITED STATES PATENT OFFICE

HAROLD B. COLVIN, OF PORT CHESTER, NEW YORK, ASSIGNOR TO BANKERS DEVELOPMENT CORPORATION, OF NEW YORK, N. Y., A CORPORATION OF DELAWARE

DESIGN FOR A SAVINGS-BANK CLOCK CASE

Application filed January 27, 1930. Serial No. 34,308. Term of patent 3½ years.

To all whom it may concern:

Be it known that I, HAROLD B. COLVIN, a citizen of the United States, and residing at Port Chester, in the county of Westchester and State of New York, have invented a new, original, and ornamental Design for Savings-Bank Clock Cases, of which the following is a specification, reference being had to the accompanying drawings, forming part hereof.

Fig. 1 is a front perspective view of a savings bank clock case, showing my new design, the dominant features of which are shown in full lines, and

Fig. 2 is a rear perspective view of the same.

I claim:

The ornamental design for a savings-bank clock case as shown.

HAROLD B. COLVIN.
